(No Model.)

J. RICHARDSON.
METAL RAILWAY SLEEPER AND TIE.

No. 430,197.

Patented June 17, 1890.

INVENTOR

James Richardson,
BY

James J. Storrs.
ATTORNEY

UNITED STATES PATENT OFFICE.

JAMES RICHARDSON, OF TARRYTOWN, NEW YORK.

METAL RAILWAY SLEEPER AND TIE.

SPECIFICATION forming part of Letters Patent No. 430,197, dated June 17, 1890.

Application filed June 7, 1889. Serial No. 313,435. (No model.)

To all whom it may concern:

Be it known that I, JAMES RICHARDSON, of Tarrytown, county of Westchester, and State of New York, have invented certain new and useful Improvements in Railways, of which the following is a full, clear, and exact description, reference being had to the accompanying drawings, and to the letters of reference marked thereon.

10 The object of this invention is to provide an improved railway; and the invention consists of metal sleepers of novel design and construction secured to and supporting the rails throughout their entire length and held 15 parallel to each other by adjustable cross ties and bars.

Reference is to be had to the accompanying drawings, forming part of this specification, in which similar letters of reference indicate 20 corresponding parts in all the figures.

Figure 1 is a plan of my improved railway with parts broken away to exhibit other parts. Fig. 2 represents a side elevation of portions of the railway, showing the manner in which 25 the sleepers may be held by the cross-ties. Figs. 3, 4, and 5 represent several forms of cross-ties and keys or wedges used with the sleeper shown in Fig. 5. Figs. 6 and 8 show an edge and a front elevation of diaphragms adapted 30 for use in a sleeper. Fig. 7 is a sectional end elevation of the railway. Figs. 9, 10, and 11 represent cross-sections of various forms of my improved sleeper and fastening devices.

In the drawings, A represents my improved 35 metal sleeper, which is preferably made of two plates of iron or steel flanged and set together so as to form a tube of elliptical cross-section with flanges at top and bottom, as shown in Figs. 1 and 7.

40 In the construction of the sleeper the lower or anchoring flanges of the plates a a are closely brought together and held by tie-rods or by bolts or rivets, (not shown,) while the upper or rail-gripping flanges are kept apart, 45 forming in the superior face of the sleeper a continuous slot of a width sufficient to receive the web of the rail B, designed for use with a sleeper of this form. This footless rail is secured in position between the upper 50 or rail-gripping flanges of the sleeper-plates partly by the form of the under part of the

rail-head, as shown in Figs. 7 and 9, and partly by bolts b (with nuts) passed through the flanges and the rail-web, as indicated in Fig. 2, and for more firmly securing the rails 55 B in place and at the same time to hold sleepers and rails adjustably parallel I employ cross-ties C and D of suitable form, as indicated in the drawings. The tie-bars C (shown in Figs. 1, 2, 3, 4, 5, and 7) have their ends 60 inserted through suitable openings made in the sleepers under the rails or through the sleeper-flanges and the web of the rails, and then the said bars are secured in place by keys or wedges d or other suitable devices, 65 which serve also to increase the grip of the rail-web by the engaging-flanges of the sleepers. The loops, hooks, or mortises f, with which the ends of the bars C are provided for the engagement of the locking keys or 70 wedges, are designed to be of such capacity that ties of standard length may be suitable for use in all parts of the road, whether straight or curved.

To further secure the sleepers and rails in 75 position to stiffen the track and to enable the sleepers to be canted, so as to adjust the position of the sleepers and rails to oppose most advantageously the lateral thrust of trains on curves, the tie-rods D have their ends passed 80 through the lower or anchoring flanges of the parallel sleepers and locked thereto. These rods may be similar in form to the upper tie-bars and similarly fastened to the sleepers, or they may have nuts g on both sides of the 85 flanges, as shown in Figs. 2, 7, and 11. In either case the lengths of the tie rods or bars between the parallel sleepers may be varied by shifting the nuts or wedges to vary the width of the track, to cant the sleepers, and 90 to bring the head of the rail parallel to the coned tread of the wheel, so that the wear of both rail and wheel shall be reduced to a minimum.

The sleeper A may be hollow throughout, 95 adequate strength for the service required being secured by the form of the plates and the thickness of the metal; or sleepers of thinner metal may be strengthened by the insertion of diaphragms E, of suitable material, as 100 shown in Figs. 1 and 6; or the sleeper may be filled with sand, concrete, or other material,

as shown at E', Fig. 7, to increase its weight and stability and to enable it to better withstand the crushing force of heavy trains. The diaphragms may be adapted in material 5 and by suitable perforations, as shown in Fig. 8, for supporting telegraph-wires or other electric conductors for which the sleeper may serve as a conduit; or such electric conductors may be supported and insulated by the 10 material with which the sleeper is filled and strengthened.

In Fig. 9 curved keys G, with a tie-bar of the kind shown in Fig. 5, are applied to a sleeper, the outer key being locked in place 15 by a wedge d, driven between the key and the sleeper.

In Fig. 10 is indicated a sleeper with a rail of the usual form held in place between its flanges by tie-rods passing through the flanges 20 and the rail-web and locked by nuts. In this case the rail-foot may rest on diaphragms or on the material with which the sleeper is filled.

Another mode of adjusting my sleeper to 25 the use of rails of the usual form is shown in Fig. 11, the rail-foot being gripped between the lips h of the two members of the sleeper. In this case, also, the rail may be partly supported by diaphragms or by the concrete or 30 other filling of the sleeper.

Other forms of sleepers and ties may be devised without departing from my invention; but in all cases the sleeper must be of 35 metal, tubular, with top and bottom flanges, and held adjustably parallel by upper and lower ties.

In constructing a railway with the sleepers and ties here described the sleepers are sunk in the road-bed to the level of the upper ties, 40 so that any lateral shifting of the track on curves is made impossible without a movement of the entire roadway. Any turning or tipping of the track under the radial thrust of trains on curves is equally prevented by 45 the form of the sleeper, by the hold which the anchoring-flanges have on the road-bed, and by the resistance offered by the bottom ties.

Tipping or spreading of the rails is made impossible by the manner in which the rails are continuously gripped and supported by the 50 upper flanges of the sleepers and held by the upper ties. The risk of broken rails is greatly diminished by the same continuous support of the rails and by the rigidity of the rail-joints--constructive features which materially favor the durability of rails and rolling-stock, the smoothness of transit, and the comfort of travelers.

This form of track, being made of easily-rolled plates and bars easily put together, is 60 comparatively cheap, is durable, is readily adjusted to varying conditions of use, and is economical with respect to maintenance and repair. It is particularly well suited for use on bridges, since the sleepers, made cellular 65 by diaphragms, are in effect strong metal beams, which, joined top and bottom by the ties into one rigid system re-enforced by the rails, may become an integral part of long 70 bridges or the whole of culvert-bridges, instead of being, as is the case with tracks supported by cross-ties, a dead load upon the bridge structure.

Having thus described my invention, I claim as new and desire to secure by Letters 75 Patent—

1. A tubular metal railway-sleeper adapted to engage and support rails lengthwise, provided with interior diaphragms, substantially as herein shown and described, whereby the 80 sleeper is made cellular, as set forth.

2. The combination, with railroad-rails, of tubular metal sleepers engaging and supporting the rails lengthwise and adjustably held in their proper relative position by metal 85 cross-ties and rods, substantially as herein shown and described.

In testimony that I claim the foregoing I have hereunto set my hand, in the presence of two witnesses, this 3d day of June, 1889.

JAMES RICHARDSON.
